J. E. RALPH.

CARD ATTACHMENT.

APPLICATION FILED APR. 4, 1907. RENEWED APR. 23, 1909.

941,273.

Patented Nov. 23, 1909.

UNITED STATES PATENT OFFICE.

JOSEPH E. RALPH, OF NEWARK, NEW JERSEY.

CARD ATTACHMENT.

941,273.

Specification of Letters Patent. Patented Nov. 23, 1909.

Application filed April 4, 1907, Serial No. 366,409. Renewed April 23, 1909. Serial No. 491,850.

To all whom it may concern:

Be it known that I, JOSEPH E. RALPH, a citizen of the United States, residing at Newark, in the county of Essex and State 5 of New Jersey, have invented certain new and useful Improvements in Card Attachments; and I do hereby declare the following to be a full, clear, and exact description of the invention, such as will enable 10 others skilled in the art to which it appertains to make and use the same.

This invention relates to attachments for cards and similar articles, and has for an object to provide a device especially and 15 peculiarly adapted for use in conjunction with the card index system forming the subject-matter of a pending application, Serial Number 299,051, filed Feb. 1, 1906, and allowed Nov. 28, 1906, although the device 20 herein shown may be employed for other purposes.

A further object of the invention is to provide a card having an edge formed for engagement with bearing or supporting 25 members removably and adjustably attached thereto for supporting the card from the under side or suspending it from the upper side.

A further object of the invention is to 30 provide a bearing member having means for engagement with a plurality of openings or recesses formed adjacent the edge of the card and with other means for removably securing the bearing member in 35 such openings.

A further object of the invention is to provide a bearing member having means for insertion within an opening spaced from the edge of a card and with means for 40 engaging the card at or adjacent the edge for securing the bearing member thereon.

With these and other objects in view, the invention comprises certain novel constructions, combinations and arrangements of 45 parts, as will be hereinafter fully described and claimed.

In the drawings:—Figure 1 is a view in side elevation of one embodiment of the present invention shown attached to a card. 50 Fig. 2 is a view in side elevation of the embodiments shown at Fig. 1 seen from the reverse side detached from a card. Fig. 3

is a view in edge elevation of the form of bearing member shown at Figs. 1 and 2. Fig. 4 is a view in side elevation of a different embodiment of the present invention shown attached to a card. Fig. 5 is a view in edge elevation of the embodiment of the invention shown at Fig. 4. Fig. 6 is a view in side elevation of one element of the bearing member shown at Figs. 4 and 5. Fig. 7 is a view in side elevation of the other element of the bearing member as shown in the embodiments at Figs. 4 and 5. Fig. 8 is a view in transverse section of the element 65 shown at Fig. 7 forming a part of the bearing member shown at Figs. 4 and 5. Fig. 9 is a view in side elevation of a different embodiment of the invention shown attached to a card. Fig. 10 is a view in edge elevation of the embodiment of the invention shown at Fig. 9. Fig. 11 is a view in side elevation of a different embodiment of the invention. Fig. 12 is a view in edge elevation of the embodiment of the invention 75 shown at Fig. 11. Fig. 13 is a view in side elevation of one of the elements of the embodiment shown at Figs. 11 and 12. Fig. 14 is a view in side elevation of another embodiment of the invention shown attached 80 to a card. Fig. 15 is a view in edge elevation of the embodiment shown at Fig. 14, and seen on arrow 15 of Fig. 14. Fig. 16 is a view in side elevation of another embodiment of the invention shown attached 85 to a card. Fig. 17 is a view in edge elevation of the embodiment of the invention shown at Fig. 16.

Like characters of reference designate corresponding parts throughout the several 90 views.

The invention forming the subject-matter of this application comprises in various embodiments a bearing member adapted to be secured at various points along the side of 95 a card and to support the card at any of such points from the under side or to suspend the card from any of such points at the upper side.

At Fig. 1 the card 20 is shown provided 100 with a plurality of openings 21 spaced from the side of the card and of any approved form, and here shown as square. To conform to the embodiment of the bearing

member shown at Figs. 1, 2 and 3 the card is also provided along the edge with notches or scallops 22 each of said notches or scallops being in alignment with and corresponding to one of the openings 21.

The embodiment of the bearing member shown at Figs. 1, 2 and 3 comprises a plate 23 slotted as at 24 from one side to form three tongues, the outer two shown at 25 10 and a central one shown at 26. The outer tongues 25 are bent as at 27 to form an angularly disposed shoulder 28, the reversely inclined sides of which are adapted to engage the reversely inclined sides of the 15 notches or scallops 22. By the formation of the shoulder 28 the tongues 25 are consequently spaced from the tongue 26 which said tongue 26 is provided with a roll or loop 29 at its extremity proportioned and 20 positioned to engage within one of the openings 21 of the card and retain the bearing member in position upon the card. It will readily be seen that by forming the bearing member of resilient material the tongue 26 25 may be flexed and the curl 29 removed from the opening 22 to permit the removal of the bearing member from the card and its emplacement within another of the scallops and openings and its consequent adjustment 30 upon the card.

As shown at Figs. 4 to 8 inclusive the bearing member comprises a plate 30 having a shoulder or offset 31 intermediate its ends and with tongues 32 formed adjacent 35 one extremity and turned toward each other and spaced to permit the introduction of the tongues 32 within one of the openings 21 of the card. For use in connection with the embodiment of the invention shown at Figs. 4 to 8 inclusive, the notches on the edge of the card are formed as shown at 22' to engage the shoulder 31 of the bearing member. The bearing member is preferably provided adjacent the end opposite the tongues 32 45 with a T-head 33 to limit the movement of a keeper 34 slidably mounted thereon and maintained in position by means of fingers 35 bent from the sides of the said keeper 34 and about and embracing the plate 30.

50 In the embodiment shown in Figs. 4 to 8 inclusive the keeper 34 is slidably moved toward the T-head 33 and the tongues 32 inserted within the openings 21 of the card whereupon with the shoulder 31 in engagement with the notches 22' the keeper 34 is slidably moved so that the fingers 35 are in engagement with the shoulder 31 and the edge of the card embraced between the keeper 34 and the off-set portion of the plate 60. It will readily be seen that by slidably moving the keeper 34 again toward the T-head 33 that the bearing member may be removed from the card and adjusted to another position.

In the embodiment shown at Figs. 9 and 10, a plate 36 is provided preferably with inturned flanges 37 to permit the engagement of a marker of some kind and with a stud 38 positioned to engage the openings spaced from the edge of the card here shown as circular and numbered 21'. Upon the plate 36 is also provided a shank or boss 39 proportioned to fit within and engage the segmental notches or scallops 22' at the edge of the card, and a turn button 40 is pivoted upon the tongue or stud 39 in any approved manner as by the rivet 41. The body portion of the turn button 40 corresponds in size and diameter to the shank 39 and to the notches 22', so that the turn 80 button 40 turned with its longitude transverse to the plate 36, the stud 38 and the shank 39 may be readily slipped into engagement, respectively, with the openings 21' and the notches 22'. When the stud 38 85 and tongue 39 are in such engagement the turn button 40 is turned so that its longitude is parallel with the longitude of the plate 36, whereupon one end of the turn button engages the card and maintains the bearing member in position.

At Figs. 11, 12 and 13 is shown a modification employing a plate 42 having a plurality of studs 43 adapted to engage an equal number of the openings 21' formed adjacent the 95 edge of the card and with a shoulder 44 positioned to bear upon and engage the edge of the card either with or without the formation of notches or scallops therein. A turn button 45 is provided pivoted upon the 100 plate 42, as at 46, and may, if desired, be provided with a ring 47 or other approved means for suspending a card thereby, it being understood, however, that the addition of the ring to the turn button does not, to 105 any degree, destroy its identity as such button.

In the embodiment shown at Figs. 14 and 15 a plate 48 is employed having a plurality of studs or bosses 49 struck up from the 110 plate and positioned to engage a plurality of the openings 21' and preferably with the studs or bosses so spaced as to engage openings with one opening intervening as shown particularly at Fig. 14. The plate is also provided with studs 50 proportioned to engage and fit within the notches 22', at the edge of the card, and an elliptical opening 51 may be provided for various purposes and preferably is formed with a boss 52 about the edge of the said opening 51 and with its upper curved end proportioned to fit and engage within one of the notches 22'. For engaging the card and maintaining the bearing member in position thereon, a plurality 125 of turn buttons 53 are preferably pivoted, as at 54, so that by turning the said turn button 53, the bearing member comprised of the

plate 48 and associated parts may be removed from the card and applied in another position.

In the embodiment shown at Figs. 16 and 5 17 the openings at and adjacent to the edge of the card are formed as single openings of key-hole shape and shown, at 54, and a bearing member is employed comprising a plate 55 having flanges 56 struck up thereon 10 reversely inclined to engage the reversely inclined sides of the openings 54 and preferably with a stud 57 proportioned to fit and engage within the segmental portion of the opening 54. Upon the stud 57 a turn button 15 58 is pivoted, as at 59, and a bearing flange 60 is preferably turned at the extremity of the plate 55 and in position to bear against the edge of the card 20.

When the turn button 58 is turned at right 20 angles to the position shown at Figs. 16 and 17, the end of the said turn button may be introduced and inserted through the circular portion of the openings 54 and when the tongue 57 and flanges 56 are in engagement 25 with the sides of the said openings the said turn button may be rotated one-fourth of a turn upon its pivot to the position shown at Fig. 16 and to engage the card and maintain the bearing member in position thereupon.

30 It will be noted that in all of the several embodiments employed a plate provided with means for engaging an opening spaced at a little distance from the edge of the card as the main feature with an auxiliary element applied thereto and adapted to engage the card and maintain the plate portion in position.

As employed to support a card in the index system described in the co-pending application, above referred to, the supporting member is applied to the lower edge of the card with the lower end of the supporting member bearing upon the elevating means described in the said application. It is evident, however, that the device may be as readily and conveniently attached to the upper edge of a card and may be employed for suspending the said card as shown at Figs. 11 to 13 or may be employed for holding a marker or tag in the specific embodiment shown at Figs. 9 and 10. The specific embodiment shown at Figs. 15 and 16 may obviously be employed either to support a card when attached to the lower side or to 55 suspend a card when attached to the upper side, the opening 51 being in such place employed for the purpose of engaging a nail or other supporting device.

What I claim is:

60 1. In a device of the class described, a plate, means provided upon the plate for engaging an opening, and means carried by the plate and spaced from and movable relative to the engaging means.

2. In a device of the class described, a 65 card provided with spaced openings adjacent its edge, and a supporting member provided with means for engaging an opening, and with means for engaging the edge of the card. 70

3. In a device of the class described, the combination with a card having spaced openings formed adjacent one edge, of a supporting member provided with means for engaging one of the spaced openings, 75 and means movable relative to the engaging means and adapted to engage one side of the card.

4. In a device of the class described, the combination with a card having spaced 80 openings adjacent one edge, of a plate provided with means for engaging one of the openings, and to position the plate upon one side of the card, and means off-set from the plate adapted and positioned to engage the 85 opposite side of the card.

5. In a device of the class described, the combination with a card having spaced openings formed adjacent one edge, of a plate provided with means for engaging one 90 of the spaced openings, and means off-set from and movable relative to the plate, and positioned to engage the opposite side of the card.

6. In a device of the class described, the 95 combination of a card having spaced openings adjacent one edge, of a plate proportioned for engagement with one side of the card and having means for insertion within one of the openings, and means off-set from 100 and movable relative to the plate, and positioned and adapted to engage the opposite side of the card.

7. In a device of the class described, the combination with a card provided with indentations along one edge, and with spaced openings adjacent the said edge, of a space adapted to engage one side of the card and provided with means for insertion within one of the openings, and means off-set from 105 and movable relative to the plate and adapted to engage the card upon the opposite side. 110

8. In a device of the class described, the combination with a card provided with spaced indentations formed along one edge 115 of the card and with spaced opening formed adjacent the said edge, of a plate adapted to engage one side of the card, means formed upon the plate for engaging one of the spaced openings, means carried by the plate 120 for engaging one of the indentations, and means movable relative to the plate and adapted to engage the card and maintain the plate thereon.

9. In a device of the class described, the 125 combination with a card having indentations spaced along one edge, and with openings adjacent the edge and spaced similar to

the indentations, of a plate adapted to engage one side of the card and provided with means for engaging one of the openings, means carried by the plate adapted to engage the sides of the indentations, and means movable relative to the plate and adapted to engage the opposite side of the card.

In testimony whereof I affix my signature in presence of two witnesses.

JOSEPH E. RALPH.
